UNITED STATES PATENT OFFICE.

JOSEPH PERNIA, OF PHILADELPHIA, PENNSYLVANIA.

COMBINATION EXCAVATOR AND PILE DRIVER.

Original application filed July 18, 1919, Serial No. 311,782. Divided and this application filed December 6, 1921. Serial No. 520,270.

To all whom it may concern:

Be it known that I, JOSEPH PERNIA, a citizen of the United States, residing at Philadelphia, in the county of Philadelphia and State of Pennsylvania, have invented new and useful Improvements in Combination Excavators and Pile Drivers, which is a division from my application bearing Serial Number 311,782, dated July 18th, 1919, of which the following is a specification.

My invention relates to new and useful improvements in combination excavators and pile drivers, and has for its object to provide in combination with an excavator frame of peculiar and unique construction, a pile driver which may be moved from one point to another along the excavator frame to place it in the proper position for driving piles ordinarily termed shoring boards.

20. A further object of the invention is to provide an excavator frame provided with certain tracks on which run suitable trucks carrying a guide for a pneumatic hammer or driver which is adapted to follow the shoring as the same is to be driven into place, the raising and lowering of the hammer and the movements of the trucks being controlled by a suitable source of power such as an engine.

30. A further object of the invention is to provide an adjustable frame which may be adjusted before being set up to accommodate the width of the trench and the height of which may be regulated according to the height of over head structures in the locality where the work is being done.

With these ends in view, this invention consists in the details of construction and combination of elements hereinafter set forth and then specifically designated by the claims.

In order that those skilled in the art to which this invention appertains, may understand how to make and use the same, I will describe its construction in detail, referring by numerals to the accompanying drawings forming a part of this application, in which:

Fig. 1, is a fragmentary side elevation of an excavator frame showing my improved pile driver combined therewith.

Fig. 2, is a vertical sectional view thereof.

Fig. 3, is a plan view of a portion of the excavator frame showing the manner in which it may be constructed to permit the

passage of the pile driver from one side to another.

In carrying out my invention as here embodied, 2 represents a trench which is being excavated for the laying of a sewer, pipes 60 or other underground objects, the side walls of the trench being held in position by suitable shoring boards 3.

Along the course of the trench to be excavated are placed a number of ties or 65 sleepers 4 to which are fastened in any suitable manner the runners or joists 5 which carry the rails 6 of the track for the excavating frame.

If found desirable the runners 5 may be 70 eliminated and the tracks placed directly upon the ties.

The conveyor frame consists of a number of uprights 7, arranged in pairs preferably converging toward their upper ends. Each 75 of the uprights of a coacting pair has bars 8 and 9 secured thereto, the former being near the lower ends and the latter near the upper ends of the uprights. These cross bars have a number of holes 10 whereby the 80 cross bars of one upright may be fastened to the cross bars of the coacting upright by means of bolts or their equivalent 11.

The lower ends of each of the coacting pairs of uprights are suitably mounted on 85 axles 12, on the outer ends of which are journaled flange wheels 13 for running upon the rails 6.

The upper ends of the supports 7 are provided with projections 14 above the upper 90 cross bars 9 and to these projections are adjustably secured the extension members 15 held in their desired adjustments by bolts 16 or their equivalent passing through the projections of the uprights and through 95 holes 17 in the extension members. These extension members carry reach members 18. The inner ends of coacting pairs of reach members overlap and are held in position or their desired adjustment by bolts 19 or their 100 equivalent passing through holes 20 in the overlapping ends.

To the reach members 18 is secured the pile driver supporting track 21, which track, if found desirable is bent to form a curve 22 105 at one end of the excavator frame so that where a single pile driver is used the same may be moved about to either side. The track 21 is preferably formed from I-beams and has mounted thereon a truck 23 which 110

consists of a suitable frame 24 and wheels 25 for running on the lower flanges of the track 21.

On the supports or uprights 7 adjacent 5 their lower ends are mounted guide tracks 26 in which runs a wheel 27 carried by the lower end of the guide 28. On this guide is slidably mounted a pneumatic hammer or pile driver 29, the same being raised and 10 lowered by means of a cable 30 wound about the drum 31 and running over a sheave 32 located in some suitable position on the excavator frame then over a sheave 33 carried by the truck, then about the sheave 34 of 15 the hanger 35 and then over the other sheave 36 carried by the truck, the opposite end being permanently fastened at some suitable point as to the excavator frame.

The truck 33 is moved along its track in 20 any desirable or well known manner, one way of so moving the truck is here shown which consists of attaching a cable 37 there- 25 to and winding said cable upon a drum 38. The different drums for actuating the dif- ferent parts of the mechanism are revolved in any well known manner and by any suit- able power as by steam, electricity or by compressed air.

The pile driver or pneumatic hammer 29 30 consists of a casing 39 provided with guide lugs 40 for engagement with the guide 28 and the hammer 41 which is actuated by compressed air, steam or other suitable operating fluid conveying to the casing through a 35 suitable pipe or hose 42 from a suitable source. The pneumatic hammer or pile driver may be constructed in any of the well known forms, wherein a suitable element will produce a sufficient blow to be trans- 40 mitted through the hammer to the shoring board or pile for driving the same into the ground.

To the cross bars 9 is secured a trolley 45 supporting track 43 preferably in the form of an I-beam on which runs a suitable trolley for carrying an excavator.

During the excavation of the trench along one portion of the operation, shoring boards or piles may be driven by mechani- 50 cal means supported by the same framework which carries the bucket trolley. To do this work the shoring boards are set in position as shown in Fig. 1 and the pile driver 29 then moved to the proper position by run- 55 ning the supporting truck 23 along the track 21 and then releasing its hoisting rope or cable 30 so that the hammer rests upon the end of the shoring board to be driven into the ground, after which the operating fluid 60 is turned on and the pile driver permitted to

follow up the shoring board as it gradually enters the ground. After the shoring board has been driven home the pile driver is raised and moved to the position of the next shoring board to be placed in position. 65

Where it is necessary to do the work very quickly and where the digging of the trench can be expedited to keep up with the work of placing the shoring boards, two pile drivers may be utilized, one on each side of 70 the excavator frame, but where the trench digging is relatively slow and one pile driver can drive the trench work, a single pile driver may be utilized on both sides of 75 the excavator frame by moving it around the curve 22 at one end of the excavator frame.

Of course I do not wish to be limited to the exact details of construction as herein shown as these may be varied within the 80 limits of the appended claims without departing from the spirit of my invention.

Having thus fully described my invention, what I claim as new and useful is:—

1. The combination with an adjustable 85 frame, of a track carried by the frame and located on the outside thereof, a truck ar- ranged to run on said track, a guide attached to said truck and depending therefrom, a wheel carried by the lower end of said guide, 90 a guide track secured to said frame in which said wheel is adapted to run and a pile driver slidably mounted upon the guide and connected with the truck so that said pile driver may be raised and lowered and trans- 95 ported from one point to another.

2. In combination, an excavator frame, parallel tracks on the outside of said frame, one above the other, a truck adapted to run on the upper track, a guide carried thereby, 100 a wheel on said guide adapted to run on the lower track and a pile driver slidably mounted on said guide.

3. The combination with an adjustable frame, of a track carried by the frame and 105 located on the outside thereof, a truck ar- ranged to run on said track, a guide at- tached to said truck and depending there- 110 from, a wheel carried by the lower end of said guide, a guide track secured to said frame in which said wheel is adapted to run, a pile driver slidably mounted upon the guide, sheaves on the truck, a cable con- 115 nected with the pile driver and running over said sheaves and a hoisting mechanism on one end of the frame with which the cable is also connected.

In testimony whereof, I have hereunto affixed my signature.

JOSEPH PERNA.
